UNITED STATES PATENT OFFICE.

RUFUS EDWARD LEE, OF WICHITA FALLS, TEXAS, ASSIGNOR OF ONE-HALF TO THE PANHANDLE STEEL PRODUCTS COMPANY, OF WICHITA FALLS, TEXAS, A CORPORATION OF TEXAS.

COTTON CLEANER.

Application filed April 20, 1928. Serial No. 271,589.

My invention relates to cotton cleaners, and has for its object the production of a machine of this class which can be used with all cotton gins of the various types employed throughout the United States, and which will possess and perform the following features and functions: (1) Means for producing a uniform and unfailing cleansing of the cotton in such a manner as to expel dirt, but without destroying the staple or machine cotton; (2) means such as beaters to force enough air through the cotton to cause the same to assume its natural fluffy stage and become animated; (3) means for preparing the cotton by breaking up the burrs, for other machinery known as burr extractors, whereby the burrs may be more easily extracted; (4) an all steel and malleable iron structure, reducing the fire risk, and which can be separated from static with one ground wire; (5) supporting spiders to be carried on shafting, preventing the beaters from breaking loose or slipping on the same, while the beaters carried on the spiders are pivotally supported whereby they tend through centrifugal force to become sufficiently rigid to function properly as flailing units and at the proper speed to be supple enough to prevent choking; (6) means for thoroughly and efficiently employing all the power absorbed by the machine; and (7) in general an assembly of parts which gives, as compared with previous machines, more thorough cleaning, less damage to the staple of the cotton, better breaking of snaps and bolly cotton, with more rigid and heavier construction, unbreakable malleable castings, closely machined, fitted and keyed on the shafting.

My invention is illustrated in the accompanying drawings, in which

Figure 1 is a side view on the side opposite the drive, with parts broken away.

Fig. 2 is an end view taken at the discharge end; and

Fig. 3 is a detail sectional view through one shaft, showing one spider and the flailing arms pivoted thereon, also the wire mesh which supports the cotton.

Fig. 4 is a diagrammatic view of a double unit installation.

Fig. 5 is a fragmentary plan view of a part of the body and shafts showing the spider arms and their flailing arms on successive shafts staggered with relation to each other.

In the drawings, 1 and 2 are steel channels

forming sills connected by and riveted to angle pieces 8 and 9, to form a rectangular frame upon which the entire structure is assembled. 3 and 4 are sheet steel sides connected by ends 6 and 7, the latter being shown partly broken away to exhibit the interior of the body. The sides and ends are riveted together as indicated at 5, and the sides are riveted to the channels 1 and 2, to form an enclosed body or receptacle for the cotton to be cleaned. Across the frame and inside the body are a series of cross bars 10, upon and between which is supported the wire mesh 11 forming a series of curved beds concentric with the several driving shafts 12, 13, 14, 15, 16 and 17. On the left-hand side in Fig. 2 I have indicated the driving mechanism, comprising the usual drive belt 18 passing around pulleys 12^a and 17^a on the shafts 12 and 17, the former of which carries a main drive pulley 19. The drive shown is what is known as a tandem drive. The cylinders or shafts are belted together as follows: 12 and 13;—12 and 14;—16 and 17;—15 and 17;— and 12 and 17. The pulleys used on this machine are of the following dimensions: 10" diameter, 6" face, and 1 $\frac{5}{8}$ " bore.

Passing through openings in the side plates 3 and 4, the shafts 12, 13, 14, etc., are journaled in bearings 20, supported on the upper horizontal faces of the channel beams 1 and 2 of the frame. Each shaft as shown herein is provided with eight spiders 21, and each spider (see Fig. 3) carries six flailing arms 22, pivoted on the extremities of its arms. These spiders and the flailing arms and all other castings are made of malleable steel, and being all electrically connected through metallic contact, can be cleared of static by attaching a single ground wire. This construction reduces fire risk. The spiders 21 are keyed to their respective shafts at 23, and are carried on sleeves 24 which surround the shaft. The length of the sleeves is such that if desired the spiders and their flailing arms may be staggered row by row, as shown in Fig. 5, those upon each shaft lying between those upon the adjacent shafts. In this way the entire surface of the cotton may be covered as it passes over the wire mesh and is beaten (see diagram of Fig. 5).

In operation, the cotton is fed in at one end and is fed out at the other, being continuously carried along by the operation of the flailing arms. Power being applied to

the pulley 19, all the parallel shafts are simultaneously turned in the same direction and all the beaters operate at once upon the cotton, which is drawn around and beneath the spiders through each concave trough until it finally feeds out of the last trough into a receiving vessel, freed of its dirt, and having assumed a fluffy stage and become animated. All dirt, dust and foreign matter not too large passes down and out through the wire mesh. Burst cotton bolly, known as bollies, which is partly open cotton pulled in the boll, are broken and prepared for the burr extractors so as to be easily extracted after passing out of the cleaner.

The wire mesh which I preferably use with this machine at present is 12-gauge screen wire, with one-half inch mesh. It will be noted that the flailing arms have no sharp points or other projections which might destroy the staple or machine cotton. In their constant revolution the beaters or flailing arms force air in each trough through the cotton, thus causing the same to fluff up and giving it life. The mass and dimensions of the flailing arms and of the spider arms are such that at a normal speed and with a normal charge of cotton, the beaters or flailing arms being fastened to the spider arms loosely, become sufficiently rigid to function properly as flailing units, and yet at the proper speed they are supple enough to give and prevent choking. The operation of these flailing arms, and the fact that the entire surfaces of the cotton are covered, produce a more thorough cleaning, with less damage to staple and cotton, better breaking of snaps and bolly cotton, than heretofore possible, within my knowledge.

The design of the parts as heretofore described permits of more rigid and heavier construction, resisting wear, also contributed to by the use of unbreakable malleable castings machined and keyed on the shafting as heretofore described.

In installing the cleaner thus described to be used on picked cotton, a single unit is set up, placed on a sub-floor behind the gin stand. The floor level of this gin stand should be approximately three feet below the top of the distributor with a separator or dropper directly over the first shaft on the end of the machine farthest from the distributor, which permits the cotton to be carried over the entire length of the cleaner screen 11 and discharged on the distributor belt.

Where a double unit is installed for the purpose of handling rough or bolly cotton and in connection with burr extracting machines, the sub-floor should be the same as mentioned for the single unit installation, but two sections should be used. The first section S is placed directly over and in line with the second section S' with the dropper

or separator D placed directly over the first shaft 17, and this section S having a discharge opening on the end nearest the distributor allowing the cotton to pass over the entire length of the screen surface and to be discharged into an all-steel chute C divided in such a manner as to place the cotton on the conveyor of a burr extractor E or by means of a by-pass C' to permit the same to pass to the second section S' of the cotton cleaner, which is located in the same manner as that described in the installation of a single unit. The cotton is thus permitted to by-pass the extractor if the operator so desires.

For operating with bolly cotton this machine is installed with an extractor E in the same manner, closing the by-pass C' between the two sections and allowing the cotton to be discharged onto a conveyer carrying the same to the extractor E, where, after having the burrs extracted, it is discharged onto a third conveyer extended over the full width of the body 4 of the second or lower section S' of the machine directly over its first shaft 90 or cylinder 17, allowing the cotton to pass over the second or lower section S' of this cleaner after it has been extracted from burrs. In this manner the cotton is cleaned before extraction, and at the same time the bolls 95 and burrs are broken up without shaling, and also at the same time prepared for extraction by the burr extractor and cleaned after the burrs have been removed.

I do not claim herein the apparatus shown in Fig. 4, nor the method of operating with said apparatus, all of which will be claimed in a divisional application about to be filed.

Having thus described my invention, what I claim is:

1. A machine unit for cleaning cotton, comprising a flat rectangular base frame composed of a pair of parallel elongated side members of structural steel connected by a pair of end members rigidly and integrally secured thereto, the upper faces of the two parallel side members lying in the same plane, a rectangular vertical enclosing body composed of side and end members of relatively thin metal coterminous with the side and end members of the base frame and secured within and upon the same, a series of journal bearings mounted upon the upper horizontal face of each side member of the base frame, outside the thin metal body, said journal bearings being in pairs on opposite sides of the base frame, each pair having a common axis and all of said axes lying parallel to each other and transverse to the upper faces of the base frame, a series of parallel driving shafts, 125 one for each pair of bearings, extending across the inside of the body above the base frame with their ends passing through the body on both sides and journaled in said bearings, a plurality of sleeves fitted upon 130

each shaft within and between the sides of the body, a plurality of spider arms upon each sleeve, and a flailing arm pivoted upon the outer end of each spider arm, a plurality of 5 cross bars extending from side to side of the base frame between and below the respective adjacent pairs of driving shafts, and parallel therewith, a foraminous metal bed extending across and within said base frame from one 10 side to the other and from one end to the other, said bed being supported upon said cross bars and formed into cylindrically curved sections between the same, each section concentric with and underlying a driving shaft at a radial distance therefrom 15

greater than the length of its spider arms, driving means mounted upon the ends of the shafts, means interconnecting said driving means, and means for applying power thereto.

2. The unit described in claim 1, in which the spiders and flailing arms mounted on successive shafts from end to end of the frame are successively and individually staggered with respect to each other, each set of spiders and arms however, acting in tandem with those preceding it on the same body of material passing through the machine.

In testimony whereof I hereunto affix my signature.

RUFUS EDWARD LEE.
